SIGNAL SYSTEM FOR CRANES

Harold L. Conrad, Oklahoma City, Okla., assignor
by decree of distribution of one-half to Myrtle
L. Conrad and one-half to Harold E. Conrad

Application June 24, 1944, Serial No. 541,930

3 Claims. (Cl. 177—311)

1

This invention relates to signalling apparatus and it has particular reference to a system for electrically transposing into audible and visible signals the load radius of a crane boom and the weight hoisted thereby.

There are many types of signalling apparatus designed to warn a crane operator at a given load moment, among which there are devices employing the pendulum principle of determining the angle of the boom and which utilize audible signals as a warning to the operator to either reduce the load or elevate the boom. The present invention seeks to improve upon these types of signalling apparatus by affording a crane operator a constant medium, disclosing to him the load weight and boom angle at all times during operation of the crane.

The principal object of the invention therefore is as stated, and further, to provide electrically actuated means for not only warning the operator of a crane against overtaxing the same, but also to keep him constantly informed as to both the weight of the hoisted load, whether or not uncalculated variations occur therein by reason of centrifugal force in swinging the boom, and the angle of the boom, all of which are important to safe handling of the crane to avoid the likelihood of overturning under extreme conditions.

Another object of the invention is to provide a signal panel consisting of parallel columns of lights, one column being indicative of the weight of a hoisted load while the other represents the load radius of the boom. As a load is hoisted, the lights in the weight column become illuminated successively upward while the lights in the load radius column are likewise illuminated and so long as the weight remains within a safe margin, only the visible signal is operative. However, provision is made that when the lights in both columns are illuminated simultaneously, an audible signal is sounded to indicate an overload, enabling the crane operator to ease off on his load or change the angle of the boom to a position of greater safety.

With the foregoing objects as paramount, the invention has further reference to certain features of accomplishment which will become apparent as the description proceeds, taken in connection with the accompanying drawings wherein:

Figure 1 is a diagrammatic view of the electrical wiring of the invention.

Figure 1A is a detail face view of the signal panel of the invention.

2

Figure 1B is a view of the boom angle indicator dial in diametrical cross-section.

Figure 2 is a detail view of the boom angle indicator circuit and the weight indicator circuit, omitting the audible signal circuit.

Figure 3 is a diagram specifically showing the bell and ringer circuits between the boom angle indicator and weight indicator with the signal lights added.

10 Figure 4 is a diagram of the bell and ringer circuits.

Figure 5 is a detail view of a type of tensiometer suitable for use with the invention.

Figure 6 is a detail view of a pendulum type 15 boom angle indicator also suitable for use in connection with the present invention.

Figure 7 is a detail view of a constant ringing drop used in conjunction with the invention.

Figure 8 is a detail view fragmentarily showing 20 the pendulum and frame of Figure 6, illustrating the dual contacts thereof, and

Figure 9 is a modified form of boom angle indicator.

Continuing with a more detailed description 25 of the drawings, it may be first pointed out that the present invention refers chiefly to the electrical system by which a crane operator is kept continuously informed concerning variations in the angle of the boom as well as variations in

30 the weight of a hoisted load. In order to accomplish this, provision is made for mechanically predetermining the tension on the dead line of a crane which represents the weight of a load supported thereby as well as provision for me-

35 chanically indicating the varying angle of the boom as it changes positions in operation. The results of these two separate components of the invention are transposed into electrical signals in a manner to be presently described which, un-

40 der normal operating conditions consist of parallel columns of lights in a panel, the lights of one column being of one color, denoting weight and the differently colored lights in the companion column denoting boom angle. As a load is

45 hoisted by the boom, the lights in the weight column are illuminated progressively upward until the actual weight of the load is disclosed on the panel opposite the column of lights. This is true also of the lights in the opposite column.

50 The arrangement is such that the lights of the weight column will not surpass those of the boom angle column unless it is desired to pick up an overload. When this occurs, an audible signal circuit is closed and remains closed until manually reset,

Referring now to the mechanical means for predetermining the tension on the dead line, previously mentioned, reference is made to Figure 5 wherein numeral 10 denotes the load supporting or dead line of a crane. Attached to this line is an angular arm 11 which, by virtue of an eye or a bolt 12, produces a bend in the line, as shown. Resisting the force tending to straighten the line is a spring 13, surrounding a rod 14, the latter being connected to the line by means of a small sheave 15. The spring and rod are arranged in a frame 16, on which is mounted a dial 17. This same reference character will be used throughout the drawings to denote the weight indicator dial. The movements of the rod 14 are transmitted to a pointer, which, on the other figures, is identified by reference numeral 18.

The tensiometer described in the foregoing and illustrated in Figure 5 of the drawings is of well known design but it is understood that any other alternative design may be used in connection with the invention as may be suited to the purpose. This applies also to the mechanical component which denotes the angle of the boom.

The inclinometer or boom angle indicating means consists in one form of a plate 19, in Figure 6, from which a segment of substantially a quarter of a circle is removed. Along the arcuate edge of the opening thus formed is arranged two rows of parallel contacts, generally designated by numeral 20. It has been found that by providing two instead of one row of contacts, current leakage, which would otherwise cause constant illumination of the signal lights, is avoided. These contacts are insulated from plate 19 by a mounting 21 of insulating material and are further insulated from each other. An expedient method of forming these contacts is to first secure two parallel wires to the mounting 21 and sever them at predetermined intervals by sawing. The resultant segments of wire then form the individual contacts 31 which are connected electrically to corresponding contacts 32 on the weight indicator dial 17. A pendulum 20a is pivoted at 20b to a corner of the plate 19 in such manner that when the boom (not shown), on which the plate is mounted, is operated, the pendulum, in remaining perpendicular to the earth, will be in a position to engage each of the contacts 31 successively. Actual engagement however is effected through the rollers 20c which are insulated apart and which are separately connected to the light and bell circuits to be presently described. A connection is also made between the pivotal point 20b of the pendulum to the source of current, comparable to the manner in which the pointer of the angle indicator dials, illustrated in companion figures, is electrically wired to the source, which will now be described.

In each of the Figures 1 to 4 inclusive, the load radius indicator is shown as consisting of a dial 24, over which operates two pointers 25 and 25a, one below the other. It is obvious that this dial, which is known as a whole circle indicator, may be substituted for the angle indicator of Figure 6, but in the form shown it is similar in function to the angle indicator illustrated in Figure 9.

The pointers 25 and 25a are provided with brush contacts 26 and 26a respectively, insulated apart and separately connected, electrically to the light circuit and bell circuit, as will become apparent presently.

The pointers 25 and 25a are caused to move in

relation to changes made in the angle of a boom by a weighted pendulum 27, suspended on a fulcrum 28 and which carries a gear 29, meshing with a pinion 30, mounted on the pointer shaft. Obviously, when the indicator is mounted on a crane boom, the pendulum 27 will remain perpendicular to the earth regardless of the angle to which the boom is moved. As the relative positions of the gear and pinion change, the latter will rotate, causing the pointer 25 to travel over the contacts 31 of the dial 24.

The individual contacts 31 of one row are connected to corresponding contacts 32 on the face of the weight indicator dial 17. The companion row of contacts 31 are connected to corresponding lights 35 of the indicator panel 34 (see Fig. 1).

The row of contacts 32 on the weight indicator dial 17 are individually connected to corresponding lights 33 on the panel 34.

Under actual operating conditions, figures indicative of the degree of angularity of the boom may be placed opposite appropriate lights on the panel 34 and figures representing weight in pounds may be inscribed opposite appropriate contacts 32 on the dial 17. However, for the sake of a better understanding of the relationship between the contacts and lights, the contacts bear numbers on the drawing corresponding to those opposite the lights. For example, contact No. 1 on the boom angle indicator dial 24 is related to No. 1 contact on the weight indicator dial 17 as well as to the No. 1 light on the panel 34.

In Figure 1, which illustrates diagrammatically the complete wiring arrangement of the inventor, it will be observed that the lower portion of the panel 34 serves as a junction box, in which the terminals 36 are mounted and to which are connected in sequence the wires 37 from the weight indicator and from one row of contacts of the angle indicator. These terminals are connected in sequence to the lights 33 indicative of the boom angle through wires 38.

Opposite the terminals 36 is a companion row of terminals 39 to which are connected wires 40 extending through conduit 41 to the companion row of contacts 31 of the angle indicator dial 24.

In Figures 1, 3 and 4, the corresponding weight and boom angle indicating circuits are shown as closed through the corresponding light, bell 42 and constant ringer 43, which indicates that a load is being hoisted with the boom at an unsafe angle. The pointers 25 and 18 of the angle and weight indicators respectively being on corresponding contacts No. 1, current from battery A flows through wire a through No. 1 light on the left side of the panel illuminating the same, thence through wire b which extends through conduit 41 to contact No. 1 on the angle indicator dial 24, thence through engaging contact 26a on pointer 25a, thence through wire c back to battery A, thereby illuminating No. 1 light denoting boom position. Simultaneously, current flows from battery B through wire d, through No. 1 light on the right side of panel 34, illuminating the same, thence through wire e to wire f, through wire g to the No. 1 contact on the weight indicator dial 17, thence through pointer 18, through wire h and back to battery B through wire i. At the same time, the bell circuit is closed through wire j which energizes the magnets 44 in the constant ringer 43 (Fig. 7), causing the armature 45 to be attracted to release the spring contact 46. Current is established through wire k to the bell 42, by engagement of spring contact

46 with the terminal 47 of wire *k*. The circuit is completed through wires *l* and *i*.

When the relay or constant ringer drop is in the position shown in Figure 1, contact points *p3* and *p4* are closed, completing the circuit and permitting current to flow momentarily from binding post C2—C3 to an insulated post 62, energizing solenoids 44, which, in turn, attract the armature 45. The hook *h* is released to cause points *p1* and *p2* to make contact. The circuit is broken between posts C2—C3 and C2 and between contact points *p3* and *p4*. The closing of points *p1* and *p2* causes current to flow between posts C2—C3 and C2, ringing the bell 42. The solenoids operate only when the contacts on the scale of the boom are synchronize.

It is obvious by reference to Figure 7 that the bell 42 will continue to ring until the plunger 48 is manually pushed upward to reset the armature 45 and spring contact 46. Simultaneous with the closing of the bell circuit as described, a red warning light 49, as shown in Figures 1 and 4 is caused to burn and, like the bell 42, is rendered inoperative only by manually resetting the constant ringer 43, as described. Shown intermediate the lamp 49 and bell 42 in Figure 3 is a green "all clear" signal 49a which is energized during inoperative periods of the warning signal.

The foregoing description deals with but a selected one of the series of individual circuits which connect the several contacts on the dials 17 and 24 with the lights and bell circuit. It is at once apparent that whenever the two pointers 18 and 25 engage corresponding contacts on their respective dials, the results are identical with those described above to warn the operator to ease off on his load or to move the crane boom to a safer angle. However, so long as the hoisted load remains within a safe margin in relation to a particular boom position, the lights in the column denoting the weight hoisted remain below and never surpass those in the column denoting the angle of the crane boom. It is apparent therefore that the operator before whom the panel 34 is mounted is at all times apprised concerning the position of the boom and the weight of the load hoisted thereby and is not required to rely upon the fixed charts and load diagrams which cannot embrace all conditions likely to be encountered.

Manifestly, the construction as shown and described is capable of some modification and such modification as may be construed to fall within the scope and meaning of the appended claims is also considered to be within the spirit and intent of the invention.

What is claimed is:

1. A signal system for boom equipped hoisting apparatus, including a signal panel carrying parallel columns of lamps, two sets of arcuately arranged and relatively spaced contacts, each set having a pointer movable thereover, one of said sets of contacts being indicative of various angular positions of the boom of said hoisting ap-

paratus and whose pointer is gravity controlled, the other of said sets of contacts being indicative of the weight of a load hoisted by said boom, means connecting the contacts of one set to corresponding contacts of the companion set, means connecting the contacts of said angle indicating set of contacts to one of said columns of lamps, means connecting said weight indicating contacts to the companion column of lamps, a current supply circuit, an audible signal circuit and means rendered operative through the connecting means upon contact of corresponding contacts of said sets by their respective pointers to close said audible circuit.

15 2. A signal system for boom equipped hoisting apparatus, two sets of individual contacts, the contacts of one set being in circuit with corresponding contacts of the companion set, a column of lamps individual to each set of contacts,

20 20 the contacts of one set being in circuit with corresponding lamps of one column, the contacts of the companion set being in circuit with corresponding contacts of the other set, a boom controlled pointer movable over the contacts of

25 25 one set, a pointer movable over the contacts of the other set and controlled by variations in the weight of a load hoisted by said apparatus, a supply circuit, an audible circuit and means for closing said audible circuit through said contact circuits when the moment of the load reaches a maximum limit.

30 3. In a signal system for boom equipped cranes, a pair of sets of relatively spaced contacts in which the individual contacts of one set are in circuit with corresponding contacts of the other set, a lamp individual to and in circuit with the contacts of each of said sets and arranged in parallel columns on a panel, means responsive to changes in the angular position of the boom

35 35 40 of said crane for closing the circuit between individual contacts of one set and their respective lamps, means responsive to variations in the weight of a load on said boom for closing the circuit between individual contacts of the other

40 45 45 set and their respective lamps, a supply circuit, an audible signal circuit and means energizing said signal circuit through said contact circuits when the boom angle and weight responsive means engage corresponding contacts of said sets of contacts.
